UNITED STATES PATENT OFFICE.

MICHAEL ZIMMERMAN, OF PHILADELPHIA, PENNSYLVANIA.

BOTTLE CRATE.

Application filed July 25, 1922. Serial No. 577,352.

To all whom it may concern:

Be it known that I, MICHAEL ZIMMERMAN, a citizen of the United States, residing at Philadelphia, in the county of Philadelphia and State of Pennsylvania, have invented 5 certain new and useful Improvements in Bottle Crates, of which the following is a specification.

My invention relates to bottle crates and 10 the object thereof is to improve, simplify, strengthen and facilitate the assemblage of crates or boxes having their interior divided, by metallic members, into compartments for receiving individual bottles, and it consists 15 in certain improvements in the structure of the box and the means of attaching the rods to the ends and sides of the crate.

These objects, and other advantageous 20 ends which will be described hereinafter, I attain in the following manner, reference being had to the accompanying drawings in which—

Figure 1 is a perspective view of a crate embodying the improvements,

25 Figure 2 is a sectional view taken on the line 2—2 of Figure 1,

Figure 3 is a sectional view taken on the line 3—3 of Figure 1, and

30 Figures 4, 5 and 6 are fragmentary perspective views showing different details of the construction.

In the drawings, the crate or box is shown having opposed pairs of walls, of which 7 35 designates sides made of a number, preferably four, of uniform wooden sections 8 abutting edgewise. Ends 9 of wood, preferably in one-piece and thicker than sides 7, are secured to the sides at lap joints 10 by fastenings 11. The vertical edges of ends 9 40 are rabbeted to receive the sides. The sides extend below the ends and are cut out at the lower corners, as indicated at 12, a distance substantially equal to the thickness of the exposed edges of the ends to accommodate the 45 ends of bottom strips 13 which are secured to the sides, as indicated, at 14 and to the ends, as indicated at 15.

A number of flat metal bars 16, preferably 50 three sets of three each, connect the sides, each set being at a different level. These bars have equidistant apertures 17, and are disposed with their flat sides in vertical planes but their ends 18 are twisted into horizontal planes and provided with apertures 19. The upper edges of sections 8, except the top sections, are provided with

recesses 20 to receive the ends 18. Fastenings 21 are passed through apertures 19 in ends 18 and downwardly into the material of sections 8 to fasten bars 16 in position. A 60 single flat bar 22, shaped like bar 16, connects the sides beneath the lower central bar 16, and has apertured ends extending into slots 23 in the lower sections of sides 7. Fastenings 24 extend up through the apertures in the ends of bar 22 and through slots 23 to secure the bar in position. This bar is provided with three sets of apertures 25, preferably of two each, equidistant between apertures 17 and between said apertures and 70 sides 7.

Ends 9 are provided with hand holes 26 near their upper edges and vertical strips 27, equidistantly spaced from each other and the sides of the crate, are secured to the inner 75 faces of the ends adjacent the hand holes. For this purpose, ends 9 are provided with recesses 28, near their top and bottom edges, and the ends 29 of strips 27 are bent at right angles to extend in the recesses 28 and provided with apertures 30. Strips 27 are anchored in position by means of fastenings 31 which take through apertures 30 in the ends of the strips.

The vertical strips 27 are provided with 80 apertures 32 in horizontal alignment with apertures 17 in bars 16 and ends 9 are drilled with sockets 33 in line with apertures 32. Rods 34 of uniform cross section take through apertures 17 in bars 16, apertures 90 32 in strips 27 and extend into sockets 33 to brace ends 9. The bottom edges of ends 9 have transverse grooves 35 extending partly across their thickness and these grooves terminate in cavities 36 extending edgewise into 95 the ends. Rods 37 take through apertures 25 in bar 22 and have hooked ends 38, preferably bent substantially at right angles and, seated in grooves 35 and cavities 36. These rods are retained in position by strips 13 100 and serve to brace the ends and keep them from spreading. Two rods 37 are disposed beneath each of the compartments into which the crate is divided by the intersecting bars and rods connecting the side and end walls to support bottles or other containers placed in the crate.

While the terms sides and ends have been used, they are to be considered interchangeable in the sense of constituting opposed 110 walls of a box or crate. Twelve compartments have been shown formed by the struc-

ture described, but it is understood that the size and number of compartments may be varied.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A structure of the class described including members provided with spaced apertures and having angular bent ends adapted to pass into recesses formed in the opposite corresponding walls of the structure, members having the ends passing through the apertures and into sockets formed in the walls, and members intersecting said second named members and anchored to the other opposite corresponding walls of the structure.

2. A crate including members provided with spaced apertures and having bent ends adapted to pass into recesses formed in the opposite corresponding walls of the crate, and intersecting rods, certain of the rods being anchored to the other opposite corresponding walls of the crate and the other of the rods having their ends passing into the apertures.

3. A crate including wall sections one above the other, intersecting members having their ends anchored between the adjacent edges of the wall sections, forming the bottom of the crate, and other intersecting members dividing the crate into compartments, certain of the last named intersecting members being anchored to the opposite corresponding walls of the upper wall section, and reinforcing members, having spaced apertures for the reception of the ends of

certain of the last named intersecting members.

4. A bottle crate having opposite walls with sockets; metal strips secured to the inner faces of the walls having apertures in registry with the sockets, and bars between the walls having their ends disposed through the apertures and into the sockets. 50

5. A bottle crate comprising opposed pairs of walls; connections between one pair of walls; apertured vertical strips having outward ends anchored in the other pair, and rods having ends taking through the apertures and anchored in the walls. 55

6. A crate having transversely extending bars; longitudinally extending tie rods disposed through the bars, and reinforcing strips having apertures receiving the ends of certain of the tie rods, the ends of the other tie rods being anchored in the walls. 60

7. A crate comprising opposed pairs of walls, one pair consisting of sections abutting edgewise, certain of the sections having seats at their abutting edges, and bars having their ends secured in the seats, tie members intersecting said bars and having their ends passing into sockets formed in the other pair of walls. 70

8. A crate comprising pairs of opposed walls, one pair consisting of sections abutting edgewise, certain of the sections having seats at their abutting edges; bars having their ends secured in the seats; reinforcing strips carried by the other pair of walls; tie rods taking through the bars and reinforcing strips and having their ends engaged with the walls, and supporting means at the bottom of the walls. 75 80

In testimony whereof I have signed my name to this specification in the presence of two subscribing witnesses.

MICHAEL ZIMMERMAN.
